BUILT-UP CONDENSER PLATE

Application filed November 26, 1930. Serial No. 498,382.

Our invention relates to condensers and particularly to the construction of condenser plates for use in high-power radio transmitters.

5 High-voltage air condensers must be constructed of plates having edges of large radius to prevent concentrated fields which would result in flashovers. In order to obtain the desired thickness of the plate, it 10 has been the practice to shrink circular plates into a pipe frame which has a recess milled therein to receive the plate edges. These circular condenser plates are expensive, hard to mount and occupy too much 15 space.

The circular plates take up too much space, both because the plate area of the corners is lost and because the mounting lugs take up considerable space. Furthermore, in any condenser plate of this type, 20 the pipe frame extends beyond the plate surface, and the plates must be spaced apart a greater distance than would otherwise be necessary, to prevent flashover.

25 Solid plates are not practical because they are heavy, costly and hard to obtain. They cannot readily be obtained in large sizes, such as from six feet to ten feet square.

The ideal shape of a condenser plate 30 would be such as to permit a spacing between plates which would progressively increase from the centers to the edges of the plates to avoid concentrated fields. This condition is approached by employing 35 plates having such large areas that the concentration of the fields at the edges of the plates is reduced.

An object of our invention is to provide 40 a high-voltage air condenser of large capacity which shall be comparatively light in weight, easily manufactured and occupy less space than high-voltage condensers formerly employed.

45 More specifically, an object of our invention is to provide an improved construction for a condenser plate of large area.

In practicing our invention, in its preferred form, we construct a condenser plate 50 of two corrugated metal sheets which are spaced apart by the corrugations. A round-

ed metallic member is positioned between the edges of the corrugated sheets to prevent sparkover.

Other features and advantages of our invention will appear from the following description, taken in connection with the drawing, in which:

Figure 1 is a plan view of two condenser plates constructed in accordance with our invention and positioned one above the other to form a two-plate condenser,

Fig. 2 is a sectional view taken on the line II—II of Fig. 1,

Fig. 3 is a fragmentary sectional view taken on the line III—III of Fig. 1,

Fig. 4 is a plan view of a modified form of condenser plate constructed in accordance with our invention, and

Fig. 5 is an enlarged sectional view taken on the line V—V of Fig. 4.

Referring to the drawing, the upper condenser plate 10 comprises a corrugated metallic sheet 11 and a second corrugated metallic sheet 12 which is placed with its corrugations at right angles to the corrugations in the plate 11. The area of the plates 11 and 12 adjacent to the edges is uncorrugated so that four metallic members 13, each having a rounded edge, may be inserted between the plates 11 and 12, as 75 illustrated. At each corner of the condenser plate 10 is inserted a metallic block 18 which has its outer edges rounded. In this way, a thick plate having a rounded edge of comparatively large radius is formed.

The lower condenser plate 14 is constructed in the same manner as the upper plate 10. In practice, as many as sixty or more condenser plates may be employed, mounted one above another and supported in any suitable manner. For example, the plurality of plates, connected, in parallel, to the lower plate 14, may be supported by a metal rod 15 at each corner. The rods 15 extend through holes 16 and serve both as supports 90 and as means for connecting the plates in parallel.

In order to make the condenser plate more rugged, the two corrugated plates 11 and 12 are preferably riveted together or spot 100

welded at the points 17 where the corrugations come into contact, as shown in Fig. 3.

The condenser plate illustrated in Figs. 4 and 5 comprises a metal pipe 20 bent to form a rectangular frame. The frame is strengthened by means of cross members 21.

A sheet of thin metal 22, such as skin aluminum, is attached to each side of the frame by means of wedges 23 driven into a slot in the pipe 20 which extends the full length of the pipe.

The metal sheets 22 are further secured to the frame by fastening them to the cross members by spot welding or the like, as indicated at the points 24.

Since various other modifications may be made in our invention without departing from the spirit and scope thereof, we desire that only such limitations shall be placed thereon as are imposed by the prior art and are set forth in the appended claims.

We claim as our invention:

1. A condenser plate comprising two metallic plates having depressions therein, said metallic plates being positioned with the depressions of one metallic plate in contact with the depressions of the other metallic plate, and a rounded conducting surface connecting the edges of said metallic plates.

2. A condenser plate comprising two corrugated metallic plates positioned with their corrugations at an angle to, and in contact with, each other.

3. A condenser plate comprising two corrugated metallic plates positioned with their corrugations at right angles to, and in contact with, each other.

4. A condenser plate comprising two corrugated metallic plates positioned with their corrugations at an angle to, and in contact with, each other, said plates having their edges electrically connected by a surface which forms a rounded edge for the condenser plate.

5. A condenser plate comprising two corrugated metallic plates which have flat portions adjacent the edges of said plates, said plates being positioned with their corrugations at an angle to, and in contact with, each other and having their edges electrically connected by a surface which forms a rounded edge for the condenser plate.

6. A condenser plate comprising two corrugated metallic plates positioned with their corrugations at an angle to, and in contact with, each other, said plates being mechanically connected at the points where said corrugations come into contact with each other.

In testimony whereof, we have hereunto subscribed our names this 17 day of November, 1930.
